UNITED STATES PATENT OFFICE.

JAMES A. H. BELLAMY, OF KANSAS CITY, KANSAS.

FOLDING BOX.

Application filed February 28, 1921. Serial No. 448,304.

To all whom it may concern:

Be it known that I, JAMES A. H. BELLAMY, citizen of the United States, and resident of Kansas City, county of Wyandotte, State 5 of Kansas, have invented a certain new and useful Improvement in Folding Boxes, of which the following is a complete specification.

This invention relates to folding boxes 10 and has for its object to produce a box of such character that it may be readily folded into a very small space when not in use.

Another object is to produce a box of this character which is unincumbered with a 15 series of complicated locking devices for securing the box in either closed or open position.

A further object is to produce a box of a character especially adapted for forming a 20 container for articles of special shape, such as a slice of pie of tapering form, the box being of such outline as to readily receive and hold a piece of pie and be conveniently carried or placed within the usual lunch box 25 without taking up an excessive amount of room.

A still further object is to produce a device of this character of comparatively durable, efficient and inexpensive construction, 30 and with these objects in view the invention consists in certain novel and useful features of construction and organization of parts as hereinafter described and claimed; and in order that it may be fully understood, reference is to be had to the accompanying drawing, in which:

Figure 1 is a perspective view of the box with the corners of the top broken away to more clearly illustrate features otherwise 40 hidden;

Figure 2 is a plan view of the box with its four walls occupying the same horizontal plane as the bottom of the box;

Figure 3 is an inside perspective view of 45 the top of the box; and

Figure 4 is a perspective view of the box with its side walls in folded position.

In the said drawing, where like reference characters identify corresponding parts 50 in all of the figures, 2 is the bottom of a box of substantially trapezoidal shape, and provided with a pair of sides 4 formed along their margins, as at 6, with a hinge of such character that the sides may be folded in 55 either direction, in order that they may abut flatly either the top or bottom face of the

bottom 2 (see Figure 4), or stand vertically upright as shown in Figure 1.

The other margins of the bottom 2 are provided with a pair of end members, a long 60 end member 10, and a short end member 12, both being provided with hinges as at 8 and 14 respectively, of such character that the ends may be folded against either the inner or outer face of the bottom 2 of the box or 65 stand vertically upright as illustrated. It will be understood in this connection that a box, either of cardboard or metal, may be made provided with suitable hinges for the operations just described, the hinges being 70 simply formed by score lines in the case of cardboard material.

By reference to Figure 4, it will be found that the interior face of the short end 12 is provided with a block 16 against which 75 the adjacent ends of the sides 4 are adapted to abut. In this connection it will be understood that no abutment will be necessary at the long end of the box as the oblique angle at which the two sides and the long end 80 come together is such that the abutting ends of the sides 4 cannot fall inward but will be retained in engagement with the adjacent ends of the end member 10, as will be clearly understood from reference to Figure 1. 85

By reference to Figure 1, it will be noted that the top 18 has downwardly extending side margins which will overlap the sides of the box and, therefore, reliably hold such sides from swinging outwardly, while the 90 contents of the box will prevent any inward folding movement of the sides.

It is believed that the impracticability of a true triangular-shaped box will be clearly apparent. If the sides abutted each other 95 at the short end of the box, they could not be folded against the same side of the box on account of their projecting corners, and if one was folded against one side of the box, and the other against the other side, 100 the long end of the box could not be folded against either side of the bottom on account of the projecting corners of the box.

From the above description it will be apparent that I have produced a folding 105 box of the character described which possesses all of the features of advantage set forth as desirable, and while I have described and claimed the preferred embodiment of the same, I reserve the right to 110 make all changes properly falling within the spirit and scope of the appended claims.

I claim:

1. In a folding box, the combination of
a bottom of substantially trapezoidal shape,
a pair of sides hingedly connected to the
bottom in such a manner that they may oc-
cupy vertical positions or flatly abut one of
the faces of the bottom, a pair of ends
hingedly connected to the bottom in such a
manner that they may occupy vertical posi-
tions or flatly abut the other face of the
bottom, and an abutment secured to the in-
terior face of the shorter end for contact
by the sides of the box.

2. In a folding box, the combination of
15 a bottom of substantially trapezoidal shape,

a pair of sides hingedly connected to the
bottom in such a manner that they may oc-
cupy vertical positions or flatly abut one of
the faces of the bottom, a pair of ends
hingedly connected to the bottom in such a
manner that they may occupy vertical 20
positions or flatly abut the other face of
the bottom, an abutment secured to the in-
terior face of the shorter end for contact
by the sides of the box, and a top member 25
adapted to retain the sides and ends in verti-
cal positions.

In witness whereof I hereunto affix my
signature.

JAMES A. H. BELLAMY.
